ELECTRIC SELF-WINDING CLOCK.

984,008.

Specification of Letters Patent. Patented Feb. 14, 1911.

Application filed October 28, 1909. Serial No. 524,638.

To all whom it may concern:

Be it known that we, WALTER H. KALLENBACH and CHARLES C. BERTSCH, citizens of the United States, residing, respectively, at 5 Jamaica Plain, Boston, and Forest Hills, Boston, in the county of Suffolk and State of Massachusetts, have invented certain new and useful Improvements in Electric Self-Winding Clocks; and we do hereby declare 10 the following to be a full, clear, and exact description of the invention, such as will enable others skilled in the art to which it appertains to make and use the same.

This invention relates to electric self-winding clocks of the type in which a spring operating constantly to actuate the clock mechanism is periodically re-wound by the automatic operation of electrically-energized winding mechanism.

20 The object of the invention, generally stated, is to produce a device of the kind above referred to which shall be reliable and positive in operation but in which the mechanism operates silently and with a minimum expenditure of electric energy.

More specifically, one object of the invention is to provide a clock of the kind referred to with a novel and simple device for throwing the electric re-winding mechanism into operation, and in this connection we employ a circuit-closing contact-member controlled directly by the movements of the clock spring. In clocks of the kind in question it has been found that the greatest economy in operation is secured by employing a spring of sufficient size to operate the clock for a considerable period of time, so that the operations of the electric mechanism may be comparatively infrequent. In such an arrangement some device is necessary for throwing the electric mechanism into operation when the spring has unwound to a predetermined extent, and since a plurality of rotations are performed by the

45 spring-actuated member during the unwinding of the spring, it has heretofore been considered necessary to provide some device, actuated by the spring barrel or some other portion of the clock train, by which 50 the electric mechanism may be thrown into operation, by closing a suitable circuit, after a predetermined number of rotations of the spring-actuated member have occurred. In our invention, however, we dispense with 55 such devices by the use of a circuit-control-

ling contact member controlled directly by the movements of the spring itself, this contact member being moved into operative position by a portion of the spring, preferably its outermost coil, when the spring, 60 in unwinding, has expanded to a predetermined extent.

Another object of the invention is to produce an electric rewinding mechanism which shall be nearly or quite noiseless, but 65 at the same time positive and reliable in operation. To this end we employ, in connection with an electro-magnet, an armature having a free vibrating movement of indefinite extent, this armature being connected with the spring by a mechanism including a one-way friction driving clutch adapted to convert the vibrating movements of the armature, whatever their length may be, into a rotary movement of the spring 70 shaft substantially without lost motion or noise. By this arrangement we avoid the buzzing noise produced by the ratchet mechanisms which have heretofore been employed in electric rewinding mechanisms 75 and resulting both from the action of the ratchets and pawls themselves and from the use of stops employed to limit and determine the vibratory movements of the armature.

Other objects and other novel features of the invention will be noted in connection with the following description of the illustrated embodiment of the invention.

40 The preferred embodiment of the invention is illustrated in the accompanying drawings, in which—

Figure 1 is a rear elevation of a portion of a clock embodying the present invention, the drawing showing the electric rewinding 95 mechanism in full together with portions of the mechanism of the clock proper. Fig. 2 is a side elevation looking from right to left in Fig. 1. Figs. 3 and 4 are front elevations, partly in section, showing in detail 100 the arrangement of the spring and the spring drum, together with the circuit-controlling contact member controlled by the spring. Fig. 5 is a front view of the driving and retaining members of the friction 105 clutch in operative position, showing in dotted lines the relative position of the driven member of the clutch.

The illustrated embodiment of the invention comprises a clock mechanism of ordi- 110

nary form together with electric rewinding mechanism. The gear train of the clock, terminating with the escapement wheel 1, is of ordinary or any suitable form and is mounted in a frame 2 of ordinary construction. The driving wheel 3 of the train is connected with a spring drum 4 which is loosely journaled upon a spring shaft 5 rotatably mounted in the frame 2, and the clock spring 6, of the ordinary spiral form, is connected at one end with the spring drum 4 and at the other end with the spring shaft 5.

In place of the ordinary winding key for turning the spring shaft 5 to wind the spring, the illustrated clock is provided with rewinding mechanism actuated by an electro-magnet 7. This magnet is of ordinary horseshoe form and is fixed to the frame of the clock by a bracket 8 secured to the yoke of the magnet.

The armature 9 of the magnet 7 is mounted upon a lever-arm 10 which is fixed to a rock-shaft 11 journaled on the bracket 8. Owing to this arrangement of the armature it is not moved directly toward and from the polar extremities of the magnet but moves transversely with respect thereto. The armature normally occupies a position somewhat below the poles of the magnet, but when the magnet is energized it acts to raise the armature to the position illustrated in Figs. 1 and 2.

In order that the armature may have an intermittent vibrating action, a contact spring 12 is fixed to the arm 10 in position to coöperate with a fixed contact screw 13. The contact screw is adjustably mounted in an insulated bracket 14 and the contact members are connected in circuit with the electro-magnet and the source of current so that when the magnet circuit is energized the contact spring acts, in a familiar manner, to interrupt the magnet circuit at each upward vibration of the armature so as to cause the armature to vibrate repeatedly.

The mechanism by which the armature is connected with the spring shaft 5 comprises a one-way friction driving clutch of which the driven member is in the form of a drum 15 fixed to the rear end of the spring shaft. This drum has an annular groove in its rear face and in this groove works the driving member 16 of the clutch. This member is in the form of an elongated dog having shoulders 17 and 18 on its opposite sides so located that when the dog is swung in one direction in the groove the shoulders act to pinch against the sides of the groove so as to prevent the dog from sliding longitudinally in the groove. The driving dog 16 has also long arcuate bearing surfaces 19 and 20 on opposite sides, these surfaces acting, when the dog is swung in the opposite direction, to afford substantially frictionless bearings

between the dog and the drum so as to permit the dog to move freely in the groove. The driving dog 16 is fixed to the upper end of a lever arm 21, and a link 22, pivoted to the lower end of the arm 21, connects it with an arm 23 fixed to and extending upward from the rock shaft 11.

The above-described mechanism is such that when the armature 9 rises the arm 23 moves to the left and the arm 21 is thereby moved in the same direction. As this action causes the driving dog 16 to pinch in the groove, as above described, the dog cannot slide longitudinally in the groove and the swinging movement of the arm 21 therefore causes a partial rotation of the clutch drum, thereby turning the spring shaft 5 and partially rewinding the spring. To insure the proper action of the clutch dog 16 it is provided with a pin 24 loosely engaging an arm 25 which is pivoted loosely upon the spring shaft 5. The outer end of the arm 25 is connected with a tension spring 26 which acts constantly to raise the arm 25 and the clutch dog, thereby maintaining the clutch dog constantly in position to pinch in the clutch groove without lost motion in the actuating mechanism. During the return movement of the clutch-driving member, the clutch drum 15 is prevented from reverse rotation by means of retaining member provided with a dog 28 similar in form to the dog 16. The dog 28 is fixed to a depending arm 29 loosely connected with the frame 2 by means of a connecting link 30. A spring 31 connected with the link 30 tends constantly to draw the retaining dog downward into position to pinch in the groove upon any tendency of the drum to rotate reversely. When the drum is rotated by the driving member, however, the retaining dog 28 is free to rise sufficiently to disengage itself from the drum. The dog 28 is retained in the groove by a left-hand extension 32 of the arm 25.

By the use of the friction clutch mechanism above described the rewinding mechanism is rendered operative without regard to the amplitude of the movements of the armature. Where a ratchet and pawl mechanism is used, as is common in devices of this character, it is obviously necessary that the armature have a movement of a given amplitude corresponding to at least the space of one tooth of the ratchet, but in the present construction the slightest movement of the armature results in a partial rotation of the clutch drum and the spring shaft, since the friction-clutch mechanism operates substantially without lost motion. For the same reason it is unnecessary to limit the movements of the armature by stops of any character and thus the armature may have a free vibrating movement, thereby avoiding the noise incident to an arrangement in which

the armature strikes against fixed stops at the ends of its vibrating movements. The electric mechanism is therefore almost absolutely noiseless. It will be noted further-
5 more that a weakening in the battery or other source of electricity by which the mechanism is energized will not necessarily cause an interruption in the operation of the rewinding mechanism even though it result-
10 in reducing the amplitude of the vibrations of the armature.

The controlling devices by which the electric rewinding mechanism is thrown into and out of operation are illustrated particularly in Figs. 3 and 4. Within the spring drum 4 is a flat spring 32 fixed at one end to the drum and carrying at its other end a contact member 33 which projects outwardly through an opening in the drum. A second contact member 34, in the form of a flat spring, is mounted upon, but insulated from, the frame 2. When the clock spring 6 is wound as in Fig. 3, the spring 32 springs inwardly into contact with the outer coil of the clock spring and holds the contact member 33 in such a position that it will not engage the contact spring 34 in the course of its rotation with the spring drum. As the clock spring unwinds, however, it gradually forces the spring 32 and contact member 33 outwardly until the contact member assumes the position in which, at the proper point in its rotation, it engages the end of the contact spring 34. By this action a circuit is closed through the electro-magnet and the battery or other source of current by which the magnet is energized, and the winding mechanism is thrown into operation. As the winding operation occupies only a few
40 seconds the rotation of the spring drum is not interrupted by the engagement of the contact members, and the contact spring 34 yields to the slight advancing motion of the rotating contact member which occurs during the rewinding operation. If, however,
45 owing to the weakness of the battery or to any other cause, the rewinding operation occupies more time than usual, the arrangement is such that the contact is automatically maintained until the winding is completed. Immediately upon the completion of the operation the circuit is interrupted, since the contact member 33 is gradually withdrawn into the spring drum as the
50 spring contracts, so that eventually it is drawn out of engagement with the spring contact member 34. By this arrangement the expenditure of electric energy is reduced to that absolutely necessary to complete the

winding operation. The positive engagement of the rotary contact member with the end of the fixed contact member gives a reliable and effective contact, and if the contact is insufficient at the first engagement it is constantly increased in force by the continued movement of the spring drum, so that an effective closing of the circuit is insured.

Our invention is not limited to the details of construction and operation of the embodiment hereinbefore described and illustrated in the accompanying drawings, but may be embodied in various other forms within the nature of the invention and the scope of the following claims.

We claim:

1. In an electric self-winding clock, the combination with an escapement train, of a spring-actuated rotary member provided with an annular groove in its rear face, friction-driving and retarding members working in said groove, an electro-magnet, an armature, means connecting said armature with the driving and retarding members, and circuit making and breaking means carried by the rotary member, for the purpose set forth.

2. In an electric self-winding clock, the combination of an escapement train, a rotary member mounted on said train and containing a spiral spring for actuating said member and provided on its rear face with an annular groove, friction-driving and retarding members working in said groove, an electro-magnet, an armature, means connecting said armature with the friction driving and retarding means, and circuit making and breaking means actuated by the spring in the rotation of said member.

3. In an electric self-winding clock, the combination with an escapement train, a rotary member mounted on said train and provided on its rear face with an annular groove, friction-driving and retarding members working in said groove, an electro-magnet having an armature, connections between the armature and the rotary member to cause the movement of the former to rotate the latter, and connections between the friction-driving and retarding means whereby the retarding means operates to hold the rotary member from reverse movement.
